UNITED STATES PATENT OFFICE.

VITTORIO PIANA, OF TURIN, ITALY.

APPARATUS FOR THE CARBONIZATION OF WOOLEN RAGS, COMBINGS, AND THE LIKE.

Application filed August 3, 1921. Serial No. 489,627.

To all whom it may concern:

Be it known that I, VITTORIO PIANA, a subject of the King of Italy, and resident of Turin, Italy, have invented certain new and 5 useful Improvements in the Apparatus for the Carbonization of Woolen Rags, Combings, and the like, of which the following is a specification.

The present invention has for its object 10 an apparatus for carrying out the so-called "carbonization" of the wool with continuous operation and under satisfactory output conditions, said "carbonization" consisting in bringing the wool into contact with gaseous hydrochloric acid for the purpose of 15 destroying all foreign matter of vegetable nature which may be mixed with the wool, such as cotton or other vegetable fibres, small chips of wood, and the like.

20 The apparatus according to this invention comprises a chamber provided with means for transporting the material to be treated and for setting inside said chamber a current of hydrochloric acid gas, as well as 25 means for the heating of the chamber.

Other advantages and features of this invention are pointed out in the following specification and in the appended claims.

The annexed drawings show by way of 30 example two embodiments of this invention.

In said drawings Figure 1 is the longitudinal section on line 1—1 of Figure 2, of a construction of apparatus; Figure 2 is the transverse section on line 2—2 of Figure 35 1; Figure 3 is the longitudinal section of a modified construction on line 3—3 of Figure 4, and Figure 4 is a transverse section on line 4—4 of Figure 3.

The construction shown by Figures 1 and 40 2 comprises a chamber 1 which is closed and protected by a suitable insulating material and a cylindrical stationary envelope or casing 2 of sheet metal located within said chamber and arranged with its axis inclined.

45 In the interior of the casing 2 is fitted a cylindrical drum 3 having its axis inclined and which is free to rotate; for this purpose it is provided, as shown, with rings 4 supported on wheels 5 mounted on inclined 50 shafts 6 which are driven by gears 7 and 8 operated by a shaft 8' and by a belt 8''.

The drum 3 is provided with inwardly

projecting arms 9 and it terminates close to the two end walls of the chamber 1 opposite a charging orifice 10 at the higher extremity 55 of the rotary drum and opposite a discharge orifice 11 at the lower extremity.

Each of these openings is traversed by a transporter consisting for instance of an endless band 12 carried by rollers 12' and 60 suitably operated by the drive of the apparatus, and includes also a closing device formed say by flexible walls 13 which are capable of reducing to a minimum the escape of gas through such openings.

At the lower extremity of the drum 3 there projects a pipe 14 for the admission of hydrochloric acid gas and in the opposite wall of the chamber 1 leading to the inside of the casing 2, is the mouth of an outlet pipe 15 for the discharge of the gas.

Lastly, into the chamber 1 and externally to the casing 2, open pipes 16 and 17 for the supply and escape of hot air derived from a suitable heating installation not illustrated, and which is compelled to come into contact with the entire surface of the casing 2 by arranging the latter so that it bears for example against the wall of the chamber 1 where the pipes 16 and 17 have 70 75 their mouths.

When the apparatus is in operation, the hot air entering by the pipe 16 heats the envelope 2 and the hydrochloric acid gas entering by the pipe 14 traverses the interior of the drum 3 in a direction contrary to the material which enters through the opening 10, and which in consequence of the rotation and the inclination of the drum 3, proceeds further and further inwards, 80 85 being continuously lifted and then dropped by the arms 9. By this process the material to be treated is subjected uninterruptedly to the action of the gas under the most favourable conditions, for, in consequence of the stirring and agitation it undergoes during its passage through the drum, it is repeatedly brought into intimate contact with the gas on all sides.

The transport of the material to be treated 100 may be effected by different methods; Figures 3 and 4 represent a construction of apparatus where is provided an endless band 18 for the purpose of transporting the ma-

terial, said band passing over rollers 19 at its extremities, one of which may be rotated by any suitable means such as by a belt gearing 20. This construction is particularly useful in connection with the treatment of delicate materials which cannot be subjected to any rough treatment or agitation without deteriorating them.

The band 18 traverses the openings 10 and 11 in the end walls of the chamber 1 in which also are arranged the flexible wall closing means 13 serving to reduce the leakage of gas.

In other respects this construction is similar to that of the foregoing example and similar members are, in both, denoted by the same reference letters and therefore it does not require further description.

Of course the casing 2 may now be arranged with its axis horizontal.

In this arrangement the material to be treated is loaded on to the band 18 at its entrance end and is fed by the band towards the interior in the direction of the arrow. This transport may take place either continuously or intermittently and it may be carried out with any desired speed so that the material which is never shifted in position and is subjected to no agitation may be left in contact with the gas for any length of time desired.

In every case the apparatus just described permits of the carrying out of the carbonization process in such a manner that the operation is a continuous one and one also permitting of the recovery of the hydrochloric acid which leaves the apparatus through the pipe 15. Besides since the warming of the gas is effected by heating the envelope 2 which is enclosed in an insulating chamber, the loss of heat is reduced to a minimum. Finally the heating of the gas is carried out without bringing the hot air into contact with the material to be treated, so that the latter is in no way soiled.

By the aid of the apparatus described, carbonization can be carried out with a great saving in fuel, in gas and in manual labour, this being due to the rapidity of the passage of the material through the apparatus, the comparatively low temperature at which the operation can take place and the indirect method of heating; for the same reasons the fibre is elastic and of good resistance and the colours are preserved entirely unaltered.

What I claim as my invention and desire

to secure by United States Letters Patent is:—

1. An apparatus for carbonizing foreign vegetable matters in woolen rags, combings and the like comprising a chamber, a closed thin-walled casing located in said chamber and leaving a space intermediate it and the walls of said chamber, gas-tight means for supplying and discharging material into and from said casing, means for moving the material through said casing from the supply end to the discharge end; means for introducing combustion gases into said chamber in the space around said casing and in contact with its wall, and means for introducing hydrochloric acid gas into said casing.

2. An apparatus for carbonizing foreign vegetable matters in woolen rags, combings and the like comprising a chamber, a closed thin-walled casing located in said chamber and leaving a space intermediate it and the walls of said chamber, gas-tight means for supplying and discharging material into and from said casing, means for moving the material through said casing from the supply end to discharge end, means for introducing combustion gases into said chamber in the space around said casing and in contact with its wall, and means for continuously supplying and exhausting hydrochloric acid gas at the two opposite ends of said casing.

3. An apparatus for carbonizing foreign vegetable matters in woolen rags, combings, and the like, comprising a chamber, a casing located in said chamber with a portion of its wall in contact with a wall of said chamber throughout its length, means for causing the material to pass throughout said casing, means for supplying hydrochloric acid gas in said casing, and means for supplying and exhausting hot air into and from said chamber, these means opening in the wall of said chamber contacted by said casing at the opposite sides of the contact portion.

4. An apparatus for carbonizing foreign vegetable matters in woolen rags, combings and the like, comprising a casing, means for causing the material to pass throughout said casing through inlet and exhaust mouths, resilient means for restricting these mouths, means for supplying hydrochloric acid gas in said casing and means for heating said casing.

Signed at Turin, Italy, July 7, 1921.

VITTORIO PIANA.
